CLAIM

The ornamental design for multi-purpose wrecking tool, as shown and described.

DESCRIPTION

FIG. 1 is a perspective view of the design; FIG. 2 is a front view of the design of FIG. 1; FIG. 3 is a side view of a first side of the design of FIG. 1; FIG. 4 is a top view of the design of FIG. 1; and, FIG. 5 is a bottom view of the design of FIG. 1.

The broken lines in FIGS. 1 and 2 illustrate aspects of the multi-purpose wrecking tool that form no part of the claim.
